CLAIM

The ornamental design for a square pail with handle, as shown and described.

DESCRIPTION

FIG. 1 is a perspective view of a square pail with handle showing my new design;

FIG. 2 is a left view thereof;

FIG. 3 is a right view thereof;

FIG. 4 is a front view thereof;

FIG. 5 is a rear view thereof;

FIG. 6 is a bottom view thereof; and,

FIG. 7 is a top view thereof.

The broken lines in the drawings depict portions of the square pail with handle that form no part of the claimed design
